J. BRADLEY

WRENCH

Filed July 5, 1922

Leo Hayes

WITNESS:

John Bradley
INVENTOR
BY *Victor J. Evans*
ATTORNEY

UNITED STATES PATENT OFFICE.

JOHN BRADLEY, OF ANGLESEA, NEW JERSEY.

WRENCH.

Application filed July 5, 1922. Serial No. 572,933.

To all whom it may concern:

Be it known that I, JOHN BRADLEY, a citizen of the United States, residing at Anglesea, in the county of Cape May and State of New Jersey, have invented new and useful Improvements in Wrenches, of which the following is a specification.

This invention relates to improvements in wrenches, the general object of the invention being to provide a wrench of the alligator type which has a pair of jaws at each end thereof, with one jaw of each pair movable with means for adjusting the same towards and from the stationary jaw.

Another object of the invention is to make the movable jaw reversible so that its toothed part may be placed in active position or its straight edge may be placed opposite the other jaw.

The invention also consists in certain other features of construction and in the combination and arrangement of the several parts, to be hereinafter fully described, illustrated in the accompanying drawings and specifically pointed out in the appended claim.

In describing my invention in detail, reference will be had to the accompanying drawings wherein like characters denote like or corresponding parts throughout the several views, and in which:

Figure 1 is a side view of the improved wrench.

Figure 2 is a section on line 2—2 of Figure 1.

As shown in these views, the wrench 1 is of double construction and each jaw part is made like an ordinary alligator wrench, excepting that the jaw 2 is pivoted in a socket 3 in the body of the wrench. The inner end of this jaw has a notch 4 which engages a nut 5 on a threaded shaft 6 which

is journaled in the body, an opening 7 being formed in the body through which the nut extends so that it can be readily manipulated by the thumb and finger of the operator. A plate 9 covers the end of the opening and forms a support for one end of the screw shaft.

Thus the distance between the two jaws can be adjusted to make the wrench fit different size objects and by removing the pivot pin 8 the movable jaw can be removed from the socket and reversed so that its straight edge may be placed in operative position with the other jaw.

It is thought from the foregoing description that the advantages and novel features of my invention will be readily apparent.

I desire it to be understood that I may make changes in the construction and in the combination and arrangement of the several parts, provided that such changes fall within the scope of the appended claim.

Having thus described my invention what I claim is:

A wrench of the class described, comprising a handle having a stationary jaw at each end thereof and a socket at each end arranged adjacent the jaw and said handle having a transverse opening therein in communication with the inner ends of said sockets, a plate closing the outer end of said opening, a threaded shaft having one end supported by said plate and its other end carried by the bottom wall of the opening, a nut threaded on said shaft, and movable thereon and movable jaws pivoted in the sockets and each of said movable jaws having a notch in its inner end for receiving a portion of said nut.

In testimony whereof I affix my signature.

JOHN BRADLEY.
